UNITED STATES PATENT OFFICE

2,580,199

NONFREEZING HYDRANT

John H. Schmid, Erie, Pa., assignor to J. A. Zurn
Manufacturing Company, Erie, Pa., a corpora-
tion of Pennsylvania

Application April 4, 1947, Serial No. 739,423

12 Claims. (Cl. 137—13)

1

This invention relates generally to hydrants and more particularly to non-freezing hydrants of the ejector type having surge tanks disposed below the frost line of the earth.

Hydrants made according to the teachings of the prior art, and with which I am familiar, have provided openings in the water line below the frost-line of the earth to provide for drainage of liquid but these openings have permitted seepage of deleterious matter from the earth and in many cases there was a cross connection with a sewer line which contaminated the water. Non-freezing hydrants having an ejector in the surge tank became flooded when the hose leading from the hydrant was kinked or when it was shut off at the nozzle thereby permitting water to stand in the water pipe above the frost line of the earth which froze and caused bursting of the water line.

It is, accordingly, an object of my invention to overcome the above and other defects in non-freezing hydrants and it is more particularly an object of my invention to provide a non-freezing hydrant which is simple in construction, economical in cost, efficient in operation, and easy to install and maintain.

Another object of my invention is to provide a non-freezing hydrant having a surge tank below the frost line of the earth containing an ejector member and associated check valves to prevent flooding of the surge tank when the flow of water is shut off above the surface of the earth.

Another object of my invention is to provide a novel arrangement of check valves in a non-freezing hydrant to prevent back flow of water into the hydrant and to prevent flooding of the surge tank thereof below the frost line of the earth.

Another object of my invention is to provide a non-freezing hydrant having a liquid receiving container adapted to be disposed below the frost line of the earth with means associated therewith for emptying the container upon normal flow of fluid, means for preventing flooding of the container when the line above the container is restricted or shut off, and means for receiving freezable liquid from above the frost line when normal flow of fluid is shut off.

Another object of my invention is to provide a novel ejector-type surge tank having a bellows-operated check valve associated therewith to prevent flooding of the surge tank when the water is shut off above the surface of the earth.

Another object of my invention is to provide a spring urged check valve in association with

2

an ejector in the surge tank of a non-freezing hydrant to prevent flooding of the surge tank.

Another object of my invention is to provide a surge tank adapted to be disposed below the surface of the earth in a non-freezing hydrant having a plurality of check valves associated therewith to prevent flooding of the surge tank regardless of any abnormal conditions in the line.

Other objects of my invention will become evident from the following detailed description, taken in conjunction with the accompanying drawings in which,

Fig. 1 is a vertical sectional view of a preferred embodiment of my novel non-freezing hydrant;

Fig. 2 is a fragmentary side elevational view with parts broken away of a modified form of surge tank and associated ejector member and check valves therein for use in a non-freezing hydrant;

Fig. 3 is a fragmentary side elevational view with parts broken away of another form of surge tank with ejector member and an associated check valve therein for a non-freezing hydrant, and

Fig. 4 is a fragmentary side elevational view with parts broken away of another form of surge tank with ejector member and an associated check valve similar to the device shown in Fig. 3.

Referring now to the drawings, Fig. 1 shows a lower body member 1 of a non-freezing hydrant having an inlet 2, laterally extending passage 3, a surge tank 4, an air vent 5, and a vertically extending valve rod receiving aperture 6. A recessed counter-bore 7 is provided in the lower portion of the surge tank 4 for receiving the lower flanged end 8 of a flanged tapered ejector member 9 having a threaded portion 10.

A cylindrical member 11 has an enlarged portion 12 on the lower end thereof having an internally threaded portion 13 for threadably engaging the threaded portion 10 of the member 8. The member 11 has a reduced throat portion 14 immediately above the ejector member 9 and an upwardly, outwardly flared portion 15 having an externally threaded portion 16 for threadably engag-

ing internal threads 17 of threaded cap member 18 in threadable engagement with an inwardly directed threaded boss 19 of the surge tank 4. A substantially right angled passage 20

extends outwardly from the ejector member 9 and leads into an enlarged counter-bore 21 threaded at 22 for threadably engaging a threaded valve seat 23. A check valve 24 having lugs 24a sealingly engages the seat 23 and prevents flow of water to the chamber 4 from member 9 where-

in the lugs 24a permit free flow of liquid in the opposite direction. The surge chamber 4 also has a depending threaded boss portion 25 for threadably engaging a threaded member 26 having chambers 27 connected by apertures 28 open to a laterally extending passage 29 leading from the passage 3 in the body member 1. A comparatively heavy cylindrical valve member 34 having legs 35 is adapted to sealingly engage the seat 33 when liquid under sufficient pressure is in the chambers 27 but which permits free flow of water when the pressure of the water is only that resulting from the head of liquid in the hydrant.

The inlet 2 of the body member 1 has a removable, threaded seat member 40 disposed therein and is engaged by a suitable valve member 41 operated through a cam lever 42 on the upper end of valve rod 43 extending through the valve rod receiving aperture 6 in the body member 1. The particular valve operating means comprise subject matter which will be claimed in another application.

The threaded cap member 18 in the upper end of the surge tank 4 has an upwardly extending, bossed threaded portion 45 for threadably engaging the threaded lower end 46 of a vertically extending water pipe 47 having a threaded upper end 48 for threadably engaging the threaded flange portion 49 of a check valve and vent member 50. The member 50 has a right angled passage 51 therein with a valve seat 52 formed at the terminus thereof which is engaged by a hinged check valve member 53 which extends substantially in parallel relationship to the vertical axis of the water pipe 47. The member 50 also has a threaded portion 54 for threadably engaging the outer threaded periphery 55 of a plug member 56 having an internally threaded bossed portion 57 eccentrically located with respect to the threaded portion 54 so that the member 50 will drain below the check valve member 53 when the hose is disconnected, for threadably engaging any suitable coupling member for connection to a hose or pipe line. A vertically extending passage 58 leading from the right angled passage 51 in the member 50 has web members 59 at the upper terminus thereof for seating a check valve 60. The upper end of the aperture 58 is enlarged at 62 and is threaded for threadably engaging an apertured vent member 63 having a valve seat 64 to provide a vent for the pipe line 47 and the surge tank 4. The check valve 60 sealingly engages the seat 64 when liquid flows under pressure but permits venting when liquid ceases to flow.

In operation, the valve handle 42 is rotated to move the valve 41 away from the seat 40 thereby permitting water to pass through the right angled passage 3 in the body member 1 upwardly through the ejector member 9 and through the member 11 to the water pipe 47 and outwardly through the member 50 to the hose or pipe disposed above the earth. When water passes through the ejector member 9 under pressure, a suction will be created in the passage 20 thereby permitting the check valve 24 to be moved from the seat 23 by the water in the surge tank 4 and permitting it to move outwardly through the passage 20 and upwardly through the member 11 to the water pipe 47 until the surge tank 4 is empty. As the water under pressure passes through the passage 3 in the body member 1, it also moves laterally outwardly through the passages 29 to chambers 21 to force the check valve member 28 upwardly

against the seat 33 to close the aperture 32 against passage of liquid from the passage 3 and passage 29 and chambers 27. When the handle 42 is thrown in the reverse direction and the valve 41 sealingly engages the seat 40, the flow of liquid through the passage 3 will be shut off and the back flow of water from the hose or pipe line will be shut off by the check valve member 53. The check valve 60 will drop and open the vent 63. Thus the liquid standing in the water pipe 41 and the water in the member 11 will pass downwardly and it will pass laterally through passage 29 and chambers 27 and upwardly past valve 34 to aperture 32 to the surge tank 4. This cycle is repeated upon the opening and closing of the valve 41.

In the event that the hose connected to the member 50 is kinked or shut off at the nozzle thereof, the surge tank 4 will not be flooded in that check valve 24 prevents water from flowing into the surge tank 4 from the member 11 and there is still enough pressure of the water in the passage 3, passage 29, and chambers 27 to move the valve member 34 into sealing engagement with the seat 33. It will thus be seen that I have provided a foolproof non-freezing hydrant which cannot be flooded no matter what the circumstances in the line.

In Fig. 2, I have shown a modified form of construction of the surge tank and associated check valve in which a body member 60 has an inlet 61, laterally extending right-angled passage 62, and a surge tank 63 having a counter bore 64 in the lower portion thereof. A tapered cylindrical member 65 is disposed centrally of the surge tank 63 and has an enlarged lower portion 66 for receiving centrally thereof an ejector member 67 having a threaded portion 68 in threadable engagement with the internal threaded portion 69 of the member 65. The lower end of the member 67 is flanged outwardly at 70 to seat in the counterbore 64 in the lower portion of the surge tank 63. The upper portion of the member 65 has a reduced throat portion 71 and an upwardly and outwardly flared portion 72 terminating in an enlarged upper threaded portion 73 threadably engaging the inwardly bossed, threaded portion 74 in the upper side of the surge tank 63. The member 65 has a laterally extending aperture 75 near the upper end thereof for receiving a pipe 76 which extends into and communicates with the inside of a bellows member 77. A cup-shaped member 78 has the open end 79 thereof threaded for threadably engaging threaded flanged portion 80 of the member 65. A seat 81 is formed internally of the chamber 82 in the member 65 and is engaged by a valve 83 having a stem 84 engaging the end 85 of the bellows member 77. Aperture 86 in the member 65 communicates with the chamber 82 of the member 65 and the surge tank 63 and the flow therethrough is controlled by the check valve 83. The member 78 has an open aperture 87 in the end thereof. Gland 89 sealingly engages the stem 84.

It will thus be seen in my modified form of hydrant that when liquid flows upwardly through the ejector member 67 into member 65, the check valve 83 will be forced to an open position and liquid will pass from the surge tank 63 through the aperture 86 and outwardly through the member 65 to a water pipe 88 extending upwardly from the surge tank 63. When the flow of water through the ejector member 67 is shut off, water pressure in the pipe 76 will not be great enough

to move the bellows 17 outwardly thereby permitting the check valve 83 to remain away from its seat 81 to permit flow of liquid through the aperture 86 to the surge tank 63.

Where the pressure above the ejector member 67 is considerable because of the kinking of the hose or the shutting off of the hose at the nozzle, water under pressure will pass through the pipe 16 into the bellows 17 causing it to expand and thereby causing the check valve 83 to move in sealing engagement with the seat 81 to shut off the flow of fluid to the surge tank 63 through the aperture 86 to prevent flooding. Pressure of the liquid on the head of the check valve 83 will also tend to move it to a closed position. It will thus be seen that in this type of ejector and check valve arrangements, all contingencies are taken care of when flow of water is shut off by the hydrant valve at the inlet thereto or shut off at any point above the surge tank or ejector.

All parts of the hydrant shown in Fig. 3 are the same as the hydrant shown in Fig. 2 except that the cup-shaped member 78 in Fig. 2 is replaced by a closed cup-shaped member 150 to which a connection is made by pipe line 151 to the inlet passage 62. Thus increase in pressure due to normal flow of fluid will cause contraction of the bellows 17 and opening of the check valve 83. Upon shutting off of the flow of liquid comparative pressure of liquid in the bellows 17 is not increased sufficiently to close the valve 83. When flow of liquid is shut off when the hose is kinked or at the nozzle thereof, pressure of liquid passing through the pipe 16 will be increased sufficiently and supplemented by the pressure exerted on the face of valve 83 to offset the pressure of the liquid in pipe 151 thereby expanding the bellows 17 and closing the check valve 83 to prevent flooding of the surge tank 63.

In Fig. 4 I have shown another modified form of my invention in which the body member 99 has an inlet 91, a laterally extending right-angled passage 92, a surge tank 93 having a countersunk recess 94 in the bottom portion thereof, and an inwardly extending threaded boss portion 95 in the upper part of the surge tank 93. A cylindrical member 96 is disposed centrally of the surge tank 93 and has an enlarged lower portion 97 forming a conical shaped chamber 98 for receiving in spaced relationship an ejector member 99 having a threaded portion 100 for threadably engaging the inner threaded portion 101 on the lower enlarged portion 97 of the member 96. The lower end of the ejector member 99 is flanged at 102 and seats in the countersunk recessed portion 94 in the bottom of the surge tank 93. The member 96 has a reduced throat portion 103 spaced above the upper end of the ejector member 99 and has an upwardly outwardly flared portion 104 terminating in an enlarged threaded portion 105 which threadably engages the threaded bossed portion 95 of the surge tank 93. The member 96 has an outwardly extending portion 106 having a right-angled passage 107 from the chamber 98 of the member 96 terminating in an enlarged counter-bore portion 108 having a threaded portion 109 for threadably engaging a threaded valve seat member 110. A check valve 111 is spaced from seat 112 of member 110 but is adapted to sealingly engage the seat 112 of the member 110 and is held in spaced relationship by a conical shaped spiral coil spring 113 secured by a spring locking clip 114.

The operation of the surge tank with the ejector member and check valve shown in Fig. 3 is

as follows: When liquid flows outwardly under pressure through the ejector member 99 to the throat 103 and upper flared portion 104 of the member 96, a suction is created in passage 107 and the valve seat 111 is moved away from the seat 112 by the water in the surge tank 73 which is thereby drawn out of the surge tank 93 and upwardly through the member 96. When flow of liquid is shut off in the ejector member 99, water passes downwardly through the passage 107 and since the valve member 111 is spaced from the seat 112 and the pressure of the liquid is comparatively small, liquid will pass into the surge tank 93 without seating the check valve 111. When the flow of liquid is shut off above the surface of the earth as when the hose is kinked or it is shut off at the nozzle, liquid will pass through the passage 107 at a greatly increased pressure, causing the closing of the valve 111 against the seat 112 and thereby preventing the flooding of the surge tank 93.

It will thus be evident from the foregoing description that I have provided a novel non-freezing hydrant having an ejector in a surge tank with associated check valves of novel design and arrangement to prevent flooding of the surge tank when the water is shut off above the surface of the earth and which still permits normal operation of the hydrant when the regular hydrant valve is operated.

Various changes may be made in the specific embodiment of my invention without departing from the spirit thereof, or from the scope of the appended claims.

What I claim is:

1. A non-freezing hydrant comprising a body member, a valve in said body member, fluid conveying connections to the upstream and downstream sides of said valve, a surge tank having an aperture in the bottom thereof adapted to be disposed below the frost line of the earth, an ejector extending upwardly from the bottom of said surge tank, said ejector being connected to said upstream connection from said valve, a riser connected to the upstream side of said ejector and adapted to extend to the surface of the ground, a casing having a passageway leading from said ejector to the lower portion of said surge tank, a check valve in said passageway for checking the flow of fluid in a direction from said ejector to said surge tank, a fluid conveying connection extending from the aperture in the bottom of said surge tank to the fluid connection on the upstream side of said valve, and a check valve in said last mentioned fluid connection to check the flow of fluid from said surge tank and normally to said surge tank except when the flow of fluid is other than upstream in said ejector, said ejector being adapted to empty said surge tank through said passageway in said casing leading thereto when water flows upstream therethrough.

2. A non-freezing hydrant as set forth in claim 1 wherein said check valve for sealingly engaging the aperture in the bottom of said surge tank is a comparatively heavy gravity operated member.

3. A non-freezing hydrant as set forth in claim 1 wherein a check valve member is disposed on the upper end of said riser to prevent the back flow of water thereto.

4. A non-freezing hydrant as set forth in claim 3 wherein an air vent with a check valve is disposed in said check valve member on the upper end of said riser.

5. A non-freezing hydrant as set forth in claim 1 wherein a check valve member is disposed on the upper end of said riser having a right-angled passage for fluid therein and a substantially vertically disposed hinged check valve for cutting off the back flow of water to said riser.

6. A non-freezing hydrant as set forth in claim 1 wherein said ejector comprises a jet member and an enclosed surrounding skirt having a reduced throat portion immediately above said jet member and an outwardly flared portion extending upwardly from the throat portion thereof.

7. A non-freezing hydrant comprising a body member adapted to be disposed below the frost line of the earth having an inlet, a surge tank having an aperture in the bottom thereof, a jet member extending upwardly from the bottom of said surge tank, passages for fluid in said body member connecting said inlet and said jet member and the aperture in the bottom of said surge tank, a surrounding enclosed skirt for said jet member in said surge tank having a throat portion immediately above said jet member and having the upper portion thereof flared upwardly and outwardly, a riser extending upwardly from said enclosed skirt for said jet member to the surface of the earth, a member extending laterally from said skirt member having a passage leading from the top of said jet member to a point adjacent the bottom of said surge tank, a check valve in said last mentioned passage for preventing the flow of fluid from said skirt member to said surge tank, a check valve in said body member normally sealingly engaging the aperture in the bottom of said surge tank to prevent the flow of fluid to said surge tank when water is passing upstream through said passageway leading to said jet member in said body member but movable from a sealed position to pass fluid to said surge tank when flow in said riser is other than upstream, and a valve for controlling the flow of fluid through the inlet in said body member.

8. A non-freezing hydrant as set forth in claim 7 wherein said surge tank has a vent leading to an upwardly extending valve rod chamber from the body portion of said non-freezing hydrant.

9. A non-freezing hydrant as set forth in claim 7 wherein said jet member comprises a threaded tapered member having an outwardly flanged base portion disposed in a recessed countersunk portion in said surge tank and said skirt member has an enlarged lower end forming a chamber around said jet member and having an interiorly threaded portion for engaging the threaded portion of said jet member.

10. A non-freezing hydrant as set forth in

claim 7 wherein a member on the upper end of said riser has a check valve to prevent back flow of water to said riser and surge tank.

11. A non-freezing hydrant as set forth in claim 10 wherein said member on the upper end of said riser has a vent with a check valve therein.

12. An apparatus for evacuating an upwardly extending fluid line when a fluid ceases to flow upstream thereof comprising an upwardly extending fluid line, a member having a fluid passageway defining an inlet connected to said fluid line, a fluid container having an aperture in the bottom thereof connected to the upstream side of said member in fluid flow relationship therewith, a valve in the passageway of said member controlling the flow of fluid therethrough, ejector means extending upwardly in said fluid line for evacuating fluid from said container when fluid moves upstream therein, a fluid connection between said ejector means and the lower portion of the interior of said container, a second fluid connection between the aperture in the bottom of said container and the downstream side of said fluid line from said ejector means for evacuating fluid in said fluid line above said ejector means and passing it to said container through said second mentioned fluid connection when fluid ceases to flow upstream in said fluid line, a check valve in said first mentioned fluid connection for directing the flow of fluid only in a direction towards said ejector means between said ejector means and said container, and a check valve in said second mentioned fluid connection between said fluid line and the aperture in the bottom of said container for normally checking the flow of fluid to said container when the flow of fluid in said fluid line is upstream but permitting the flow of fluid to said container when there ceases to be a flow of fluid upstream in said fluid line.
